(57) CLAIM

The ornamental design for the multi-use utility vest for holding smaller personal items, as shown and described.

DESCRIPTION

FIG. 1 is a front view of the multi-use utility vest for holding smaller personal items, with the elastic straps shown secured for fit;

FIG. 2 is a rear view thereof;

FIG. 3 is a front view, with the elastic straps shown unsecured;

FIG. 4 is a rear view thereof; and,

FIG. 5 is a top view, shown laid out flat.

The vest is flat and has no thickness, as shown in FIG. 5 where the vest is laid flat.
